WORM FEEDER

Harding W. Willinger and Herbert N. Nestler,
New York, N. Y.

Application April 21, 1954, Serial No. 30,121

Term of patent 7 years

(Cl. D91—2)

FIG. 1.

FIG. 2.

FIG. 3.

FIG. 4.

Fig. 1 is a side elevational view of a one piece tie down showing our new design;

Fig. 2 is a top plan view thereof;

Fig. 3 is a slightly enlarged perspective view thereof, and

Fig. 4 is a cross-section of Fig. 1 taken along line 4—4 thereof.

We claim:

The ornamental design for a worm feeder, substantially as shown.
